UNITED STATES PATENT OFFICE

149,426

DESIGN FOR A GUITAR

Leonard L. Lademann, Detroit, Mich.

Application October 25, 1946, Serial No. 134,239

Term of patent 14 years

(Cl. D56—1)

To all whom it may concern:

Be it known that I, Leonard L. Lademann, a citizen of the United States, residing at Detroit, in the county of Wayne and State of Michigan, have invented a new, original, and ornamental Design for a Guitar, of which the following is a specification, reference being had to the accompanying drawing, forming a part thereof.

I claim:

The ornamental design for a guitar, as shown.

LEONARD L. LADEMANN.
